ORVAL J. CUNNINGHAM, OF KANSAS CITY, MISSOURI.

ANESTHETIC APPARATUS.

1,129,171.

Specification of Letters Patent. Patented Feb. 23, 1915.

Application filed January 24, 1913. Serial No. 743,986.

To all whom it may concern:

Be it known that I, ORVAL J. CUNNINGHAM, a citizen of the United States, residing at Kansas City, in the county of Jackson 5 and State of Missouri, have invented certain new and useful Improvements in Anesthetic Apparatus, of which the following is a specification.

This invention relates to anesthetic apparatus for administering nitrous oxid and oxygen with the ether sequence.

The apparatus embodying the invention is characterized by the following, and other, advantages: less disagreeable to the patient because of the induction of anesthesia by nitrous oxid and oxygen, rendering the patient unconscious of the irritation from the ether vapor afterward given; quick induction of anesthesia, shortening the time of 20 the most dangerous stage of anesthesia; prevention of cyanosis and clonic spasm, by the use of oxygen; ether vapor is given in a measured dosage by means of a valve provided with a dial and index, permitting a 25 constant, or perfectly graduated, administration; less danger of pneumonia consequent because from 30 to 60 degrees Fahrenheit of refrigeration is obviated by warming the inhalation, no flame nor electricity being employed for the purpose; less danger of aspiration pneumonia and after-sickness, because of the form of dosage producing less oral secretion than by other methods; less danger of overdosage, because the 30 anesthetist has at all times a knowledge of the dosage the patient is receiving; oxygen can be given instantly if at any time the patient begins to show untoward symptoms; economy in the use of ether; thorough mixture 40 of air, gases, or both with the etheric vapor; nitrous oxid, oxygen, ether vapor and air may be given separately, or in any combination.

The invention comprises, further, a novel 45 mode of and apparatus for, pumping the inhalation to the patient in cases where the usual inhalation method can not be employed.

In order that the invention may be fully 50 understood, reference will now be made to the accompanying drawings, in which:—

Figure 1 is a top view of the apparatus without gas flasks; Fig. 2 is a top view, the top plate being removed and certain parts 55 broken off; Fig. 3 is a vertical section taken on line III—III of Fig. 1; Fig. 4 is a ver-

tical section taken on line IV—IV of Fig. 1; Fig. 5 is a side view of the air and gas valve, detached; Fig. 6 is a side view of the ether valve, detached; Fig. 7 is a bottom 60 plan of the apparatus, the bottom plate being removed, the gas arms in section, and holding the necks of gas flasks in section; Fig. 8 is a longitudinal vertical section taken on line VIII—VIII of Fig. 7, omitting 65 said flasks and showing gas-bags connected to the apparatus; Fig. 9 is a horizontal section through the ether chamber, taken on line IX—IX of Fig. 4, the valves being omitted; Fig. 10 is a diagrammatic 70 sectional view of my novel pumping attachment.

General description.—1 designates a case or housing which contains the ether chamber, the water chamber, the regulating 75 valves, and the various ports and passages. The case is provided with an arm 2 for the attachment of steel flasks containing nitrous oxid under pressure, and with an opposite similar arm 3 for the attachment of flasks 80 containing compressed oxygen. The bottom 4 of the case has two flanged openings 5 and 6 to receive coupling necks of gas bags N and O, which are charged from the respective nitrous oxid and oxygen flasks. Plate 85 4 is also provided with a central boss 7 in which is a threaded socket 8 for the reception of the upper end of a standard (not shown) that supports the whole apparatus at a convenient height. The air intake, A, 90 is in said bottom plate 4.

10 is the coupling sleeve to which the inhaler tube 12 is connected when a mask is used. In some cases an attachment, such as shown in Fig. 10, is interposed between the 95 inhaler-tube and the sleeve 10.

Within the case 1 are two integral, tapered valve seats 14 and 15 which respectively inclose two plug valves 16 and 17. These valves have the outward form of cone 100 frustums, being tapered to fit their seats and having knobs 18, 19 by which they may be turned. Valve 16 is the ether valve, and valve 17 regulates the quantities and proportions of air and other gases supplied to 105 form the full mixture.

20 is a horizontal partition forming the bottom of a liquid-ether chamber E. The top of said chamber is formed by a rigid partial diaphragm 21, between which and the top plate 22 are two shallow chambers or passages E' and H. Diaphragm 21 cov-

ers the entire area inclosed by the outer walls of the case, except for the valve-seat openings 24, 25, the narrow tapered port 26, and certain other apertures hereinafter mentioned.

5 W is a water chamber, located immediately below the ether chamber E, and surrounding the walls 27 of a duct I that leads from the ether valve 16 to the coupling 10.

10 Plate 4 is the bottom of the water chamber. Said chamber has an inlet 28 and an outlet 29, which are closed with screw plugs 30 and 31 respectively.

15 Ether chamber E has an intake 32 and an outlet 33, which are closed with screw plugs 34 and 35 respectively.

20 Valve-knob 18 is provided with a pointer 36, which plays over a dial provided with a circular rib 37—38, the part 37 being higher than part 38 and forming stops for the extreme positions of the valve. Cut in part 38 are a series of notches 39, each of which is marked with percentage figures as shown. The pointer is resilient and takes into any

25 of said notches. Similarly, valve-knob 19 has a pointer 40, slideable upon a circular rib 41 having terminal notches marked "Air" and "N₂O" respectively and a series of intermediate notches 42, numbered substantially as shown, one being marked "Oxygen."

30 *Detailed description.*—Figs. 7 and 8.—The arm 2 is united with the case 1 by a stem 43, in which is a duct 45 connecting 35 with a duct 46 through the arm, and with a small short tube 47 which stops at or near the mouth of bag N. At the ends of duct 46 are metal nipples 49, each provided with a rubber washer 50. The ends of arm 2 have 40 integral yokes 51, adapted to receive the necks 52 of flasks (not shown) containing compressed nitrous oxid. These necks have the usual nipple seats and bores 52' and also have conical sockets for the ends of clamping screws 53. Said screws are of sufficient 45 length to have their ends seated in the orifices of nipples 49, so that when only one flask is being used no gas can escape to the atmosphere from the flask in use. The opposite gas arm, 3, is shown as a duplicate in 50 all respects of that just described; the necks 55 being those of oxygen flasks.

55 From the gas intake 5, a passage 59 leads to a vertical passage 60, which communicates with a small rectangular port 61 in valve-seat 15. From the other gas intake 6, a passage 62 leads to a port 63 in valve-seat 15. A third port 65 is cut through said valve-seat, opposite the port 61, and communicates with an air-intake chamber 66, which receives air from atmosphere through opening A.

60 The lateral walls of the passages 59 and 62, and of chamber 66, are integral with the 65 valve-seats and water-chamber walls, and

stand flush with the bottom plate 4. One of these walls is a continuous flange 67 extending around and below the valve-seats. The bottoms of the valve-seats are spaced above plate 4 and there is free communication between the interiors of the valves 16, 17 through said space.

67 The air and gas valve 17 is provided with two ports, 69 and 70, and has a horizontal slit 71 communicating with one side of port 69. Port 69 will register with valve-seat port 63, and port 70 will register with valve-seat port 61. When the valve's pointer is at "Air" the air ports 70 and 65 are open, but the gas ports 69 and 63 are closed. By turning the valve clockwise (as seen from above) the gas ports 63, 69 are initially opened just as the air ports 65, 70 begin to close. Further rotation of the valve gradually increases the opening of the gas ports and decreases that of the air ports. After the air is fully cut off, gas port 63 remains open until the valve port 69 passes it. In this position the valve-slit 71 will be in communication with port 63, thereby passing only a minute stream of one gas through said port. The foregoing refers to the gas issuing from the adjacent bag O, or oxygen. The other gas, supplied from bag N, is first admitted through port 61 after the air port has been closed, and when port 61 is open the other gas port and the air port are closed, excepting that the slit 71 will permit a certain flow through port 63. This valve 17 has no stop to prevent its being turned a full revolution by the operator. Said valve is pressed upward by a spring 72, acting through a collar on a vertical rod 73 whose lower end is slidably mounted in a hole in a bearing-piece 74 which supports the spring 72 and is secured to an ear 75 and extends to a point below the axis of the other valve 16, where it supports a pressure spring 76 and rod 77 that act on said valve. Thus both valves are held to their seats so that any wear will be automatically taken up and leakage prevented.

100 Referring now to Fig. 9: The liquid-ether chamber E is here shown in plan, and its bottom 20 covers virtually the horizontal 105 area of the case except for the valve openings 24, 25. In the valve-seat 14 (of the ether valve 16) are two opposite ports 80 and 81. Around said ports, respectively, are integral walls 82 and 83, which are curved 110 outwardly to provide spaces 84, 85, having bottoms 86, 87. The walls 82, 83 at their tops are integral with the partial diaphragm 21, and said walls shut out the liquid ether from the ports 80, 81 one of which 115 is below the surface of the ether in practice. The partial diaphragm 21, which is integral with the case walls 1 and is spaced above the plate 20, is shown in plan in Fig. 2. Besides the aforesaid openings 24, 25, 84, 85, 28 120

and 32, this plate contains three narrow ports 88, 89 and 90, all located as far as possible from the tapering port 26, and distributed along the side of the case opposite said port. Port 90 communicates with port 26 by way of a passage 91. (Fig. 9). Port 89 communicates with port 26 through a passage 92 (Fig. 9) and port 88 communicates with port 26 through a passage 93. (Fig. 9).
 5 It will be observed that the partial dia-
 phragm 21 is provided with diametrically
 arranged ribs 94, which merge into the
 valve-seat walls and the outer case walls
 and meet the top plate 22 of the case. These
 10 ribs partition off the ether-vapor chamber
 E^v from a similar chamber H; the former
 being in connection with recess 85, and the
 latter with recess 84.

The air, gas or mixture that comes
 20 through the valve 17, passes from the bot-
 tom of said valve to, and enters at, the bot-
 tom of the ether valve 16. Passing through
 said valve as hereafter described, the gases
 escape through port 80 and recess 84 into
 25 the shallow chamber H, having the out-
 lets 88, 89, 90, through which the gases
 are drawn into the liquid ether chamber
 E above the liquid ether therein. Being
 drawn over the surface of said liquid and
 30 becoming etherized thereby, the gases must
 pass clear across the said surface in order
 to pass through the taper port 26 into the
 chamber E^v, from which the mixture enters
 recess 85 and passes through port 81 into
 35 the ether valve 16. The ribs 94 prevent
 the gases or air from short-circuiting from
 chamber H to chamber E^v above the dia-
 phragm. The ether valve 16 is so construct-
 ed, however, that all or any proportion of
 40 the gases employed (whether atmospheric
 or not) may pass into the inhaler tube pas-
 sage I without passing over the ether. In
 practice the ether vapor is sometimes only
 five per cent. under operating room con-
 45 ditions.

The ether valve seat 14 has besides the
 ports already mentioned, a third port 96
 which opens directly into the passage I
 as shown in Fig. 3.

50 In the valve 16 are four ports, 97, 98, 99
 and 100. The topmost port, 97, tapers at
 one end as shown at 97' to an acute end, the
 opposite end having the full width of the
 port. Below said port is a partition 101,
 55 which extends downward in a spiral manner
 to nearly the bottom of the valve. Just
 below the upper portion of said partition
 is the second port 98, which has the same
 shape as port 97 but has a different angular
 60 position, its acute end 98' being below the
 widest portion of port 97. Separated from
 port 98 by the partition 101, is the third
 port 99, which is similar in form to port
 97 and occupies the same angular position
 65 thereof. Ports 97 and 99 are in free com-
 munication through the interior of the valve,
 and the partition 101 forms the inner and
 lower surface of their connecting passage.
 The lowest port, 100, is similar in shape to
 70 the other ports, is opposite to port 99, and is
 reversely arranged with respect to its taper
 portion 100'. This port is cut off from port
 99 by the partition 101, but has free com-
 munication with port 98, and is on the same
 75 side of the valve. Either of ports 99 and
 100 is adapted to register with seat port
 96, according to the position of the valve.
 When said valve 16 is in its initial position,
 ready for use, its port 100 is in full register
 80 with seat port 96 to passage I. At this
 time, both seat ports 80, 81 are closed, so
 that the gases by entering the valve will
 pass directly into said passage I. When the
 valve knob is turned clockwise, port 96 is
 85 gradually closed, and when it is nearly
 closed, the ports 80, 81 are initially opened
 to valve ports 97, 98. As the valve turns
 clockwise, the ports 80, 81 are farther opened
 and the percentage of ether thereby in-
 creased. The valve's partition 101 cuts off
 90 the gas from port 81 but admits it through
 valve port 98 and seat port 80 into the shal-
 low chamber H from which it passes down
 into the ether chamber E across same, up
 into chamber E^v, thence through seat port
 95 81 into the valve 16, thence through seat
 port 96 into the passage I. The figures 1 to
 15 on the dial of the other valve 17, show
 percentages of oxygen that may be used
 with nitrous oxid.

100 The operation will be as follows: If oxy-
 gen or nitrous oxid, or both, are to be used,
 the proper flasks are attached to one or both
 of the arms. A suitable quantity of water
 at a temperature of 90 degrees Fahr. is
 105 introduced through the opening 28 of the
 case. If a mask is to be used on the patient,
 the inhaler tube is connected at 10 and the
 mask to said tube. If an insufflation device,
 nasal catheter or tube to mouth is used, my
 110 attachment shown in Fig. 10 and presently
 described, will be employed. The ether
 pointer 36 is placed at zero, and the air-
 gas pointer 40 is turned to the point marked
 N₂O and then backward to a figure that
 115 corresponds with the percentage of oxygen
 to be administered. As soon as the patient
 is anesthetized, the ether valve is gradually
 turned clockwise until there are indications
 that the patient is etherized. At that time,
 120 the air valve is turned back to the point
 marked "Air" in order to replace the
 nitrous oxid and oxygen with air. It will
 be evident that by adjusting the two valves,
 any desired combination of air, nitrous oxid,
 125 and oxygen may be administered, and that
 ether alone may be given without discon-
 necting the gas containers from the appa-
 ratus. The gas bags N, O receive measured
 130 quantities of gas from the flasks when the

valves of the latter are opened, and deliver same to the apparatus in the manner hereinbefore described. The water bath, which reduces the usual refrigeration, drops to the 5 temperature of the room, after which it absorbs sufficient heat from the air of the room to perform its function.

To administer oxygen, unmixed with other gas, the operator simply turns the pointer 10 to the position marked "Oxy". This turns valve 17 to such a position that the oxygen inlet 6-62 is placed in direct communication with passage I, by way of ports 63, 69, through valve 17, into valve 16, 15 through ports 100 and 96. A few breaths of oxygen will completely relieve the occasional laryngeal spasm of incomplete anesthesia without decreasing the amount of ether being used. This effect cannot be produced by air, although the oxygen of the 20 air is usually sufficient if there is no re-breathing. In routine work, I use oxygen only during the administration of nitrous oxid.

25 Mixed with nitrous oxid, the oxygen is valuable in its effect of minimizing certain disagreeable after-effects.

When about to employ an insufflation device, a nasal catheter, or a tube to mouth, I 30 disconnect the inhaler tube 12 and attach a valve-case R (Fig. 10) provided with a connection 103 for inhaler tube, a connection 104 for a pump, and a connection 105 for a pressure equalizer. Said valve case comprises 35 three telescopically arranged tubes, 103, 106 and 107. Tube 107 fits within the sleeve coupling 10 and has an exterior bead 108, also at its end a valve seat 109 for a soft rubber disk valve 110, which is mounted 40 on a crosspiece 112 by a screw 111. Between nipples 104 and 105, a second valve 113 is seated upon the outer end of tube 106, being mounted like valve 110. The inhaler tube coupling 114 fits the tube 103.

45 115 indicates a single-acting foot-pump, the piston of which is raised by a spring 116. The pedal 117 is mounted on the piston rod. The port 118 is connected by a tube 119 with nipple 104.

50 120 is a rubber bag or other resilient chamber, capable of expansion and contraction, and has its neck fitted into the nipple 105.

During the administration one assistant 55 operates the pump 115. By each down stroke of the piston, air is forced past valve 113 into the inhaler tube; valve 110 preventing said air from entering the passage I. By every up stroke of the piston, air and ether or gas and ether are drawn from the case 1 60 into tube 119 and the pump cylinder, while the equalizer 120 by contracting supplies the patient with the fluid. In practice I have found the operation of this attachment satisfactory.

65 Having described my invention, I claim

as new and desire to secure by Letters Patent:

1. A case having separate intakes for two gases and air, and a common outlet; means for mixing said gases with air before entering said outlet, means for drawing air or gas and air over liquid ether, and a valve to control the proportions of air and gases. 70

2. A case having a liquid-ether chamber and an air intake; a partial diaphragm extending horizontally above said chamber, said diaphragm having ports through opposite sides thereof, a valve adapted to admit air through a port at one side and receive etherized air through a port at the other 80 side, and means to prevent mixture of said air and etherized air above said diaphragm. 75

3. A case having an air intake, an air and ether outlet, and a horizontally disposed liquid-ether chamber; a horizontally extending partial diaphragm spaced between the top of the case and the bottom of said chamber, a full partition across the case between said top and partial diaphragm, a valve seat proximate to said diaphragm and having 90 two ports both communicating with the space above the diaphragm, a valve in said seat, having two ports adapted for respective registration with the valve-seat ports, said diaphragm having ports therein at opposite sides of said partition, a partition in the valve, separating the valve ports, and a passage from one valve port to said outlet. 95

4. A case, having separate intakes for air and a gas, and a common outlet for both; two chambered valve-seats in said case, the chambers of said seats being in constant communication with each other, said case having passages from the air and gas intakes to one valve and a passage from the other valve to 100 said outlet; and suitably ported valves in 105 said seats.

5. A case having three separate intakes for air and two gases, and a common outlet for all; two chambered valve-seats in the 110 case, the chambers of said seats being in constant communication with each other, said case having a passage from each gas intake to one valve, a passage from said valve to their intake, and a passage from the other valve to said outlet; and suitably ported valves in 115 said seats.

6. A case having two chambered and ported valve-seats, two valves mounted in 120 said seats and having suitable ports, means permitting air to flow through said valves in succession, and means permitting a gas to flow through said valves in succession and mingle with the air.

7. A case having two chambered and ported valve-seats, two valves mounted in 125 said seats and having suitable ports, an ether-vaporizing chamber having ported communication with one valve, means permitting air to flow through said valves in 130

succession, thence through said chamber, thence back to the second valve, and means to permit a gas to follow and mingle with the air.

5 8. A case having two ported valve-seats, two suitably ported valves mounted in said seats, an ether-vaporizing chamber having ported communication with one valve, means permitting air to flow through said valves 10 in succession, thence through said chamber, thence back to the second valve, and means permitting two different gases to follow and mingle with the air.

9. A case, a tubular valve-seat therein 15 having three ports at different heights; a chambered plug valve in said seat, said valve having an air-and-gas intake and four ports, the upper two valve ports being registrable with the adjacent seat-ports, the lower two 20 valve ports being registrable with the lowermost seat port; a duct from the last named port to an inhaler-tube, means for admitting air and gases to said valve intake, and an ether chamber having an inlet and an outlet 25 communicating with the upper two valve-seat ports.

10. In combination, a case provided with an outlet for anesthetic, a valve chamber connected to said outlet, two valves in said

chamber, each opening in the direction of 30 flow, a single-action pump connected with said chamber between said valves, and an equalizer connected with said chamber beyond the second valve from the case, and an inhaler tube connected to the valve chamber 35 beyond the last named valve.

11. In an anesthetic apparatus, a casing containing a shallow horizontally disposed liquid-ether chamber, means for continuous induction and eduction of air at opposite 40 sides of said chamber, a water-bath contiguous to said chamber, a regulating valve, an inhalation tube, and a passage partly 45 enclosed by said water-bath and connecting said valve with said tube.

12. In an anesthetic apparatus, a casing, an inhalation tube connected thereto, a valve in said casing, a water-bath within said casing, and a passage extending through said 50 water-bath and connecting said valve with said tube.

In testimony whereof I affix my signature, in the presence of two witnesses.
